UNITED STATES PATENT OFFICE.

HENRY WESTON, OF PHILADELPHIA, PENNSYLVANIA, ASSIGNOR TO THE
S. S. WHITE DENTAL MANUFACTURING COMPANY, OF SAME PLACE.

DESIGN FOR DENTIST'S PLIERS.

SPECIFICATION forming part of Design No. 27,637, dated September 14, 1897.

Application filed June 7, 1897. Serial No. 639,761. Term of patent 14 years.

To all whom it may concern:

Be it known that I, HENRY WESTON, a citizen of the United States, residing at Philadelphia, in the county of Philadelphia and State 5 of Pennsylvania, have invented a certain new and useful Design for Dentists' Pliers; and I do hereby declare the following to be a full, clear, and exact description of the invention, such as will enable others skilled in the art 10 to which it appertains to make and use the same.

The leading feature of my design consists of the jaws having the peculiar compound lateral and vertical curves, as shown in the 15 accompanying drawings, in which—

Figure 1 is a side elevation of the implement; Fig. 2, a top plan or edge view, and Fig. 3 a vertical section on the lines 3 3 of Figs. 1 and 2.

20 The pliers or tweezers consist of the connected handles A A, provided with the jaws B B, which at a short distance from or in

rear of their points C C are laterally bowed or curved outwardly or away from each other, so as to leave an approximately elliptical 25 space between them, and which are also curved vertically or in the plane of the flat side of the implement. The jaws also have their corners rounded or are substantially elliptical in cross-section, as shown in Fig. 3. 30

Obviously this design is applicable to pliers, tweezers, forceps, and similar implements of various kinds.

I claim as my invention—

The design for a pair of dentists' pliers, 35 tweezers, &c., substantially as shown and described.

In testimony whereof I affix my signature in presence of two witnesses.

HENRY WESTON.

Witnesses:

JOHN A. CODDING,
GEO. B. TAYLOR.
